UNITED STATES PATENT OFFICE.

FREDERICK M. MELVIN, OF LA PLATA, MISSOURI.

PLURAL-DISK CUSHION CLUTCH.

1,407,561.

Specification of Letters Patent. Patented Feb. 21, 1922.

Application filed February 9, 1921. Serial No. 443,730.

To all whom it may concern:

Be it known that I, FREDERICK M. MELVIN, a citizen of the United States, residing at La Plata, in the county of Macon and State of Missouri, have invented a new and useful Plural-Disk Cushion Clutch, of which the following is a specification.

The object of my invention is to provide a novel cushion friction clutch for controlling or regulating the operation of the steering gear on Ford automobiles; and to provide novel combinations of disks adapted to accomplish the desired end. I attain these and other objects of my invention by the mechanism illustrated in the accompanying drawings, in which—

Figure 1 is a vertical section of the invention applied to the steering gear of the type disclosed;

Fig. 2 is a perspective view of disk 7;

Fig. 3 is a perspective view of disk 8;

Fig. 4 is a perspective view of disk 10;

Fig. 5 is a transverse sectional view through one arrangement of my disks;

Fig. 6 is an edge elevational view of a modified arrangement of the disks;

Fig. 7 is an edge elevational view of another arrangement of the disks;

Fig. 8 is still another arrangement of disks; and

Fig. 9 is a perspective view of the modified disk 11.

Like numerals designate like parts in each of the several views.

Referring to the accompanying drawings, illustrating my invention, the conventional steering gear casing 1 is shown, having the screw top 4 inclosing the steering gear 5, which is mounted on steering post 3, which latter member carries the steering wheel 2, all being of conventional type. Mounted on steering gear 5 I provide a metal ring-shaped disk 7, on which is mounted a second metal ring-shaped disk 8, said disk having suitable protrusions 9, adapted to frictionally engage a suitable cushion disk of thick flexible material, such as, felt, leather, rubber, or an equivalent substance or structure. In lieu of the disk 8 I may provide a corrugated ring-shaped disk 10; or, I may provide a squared disk 11 hav-

ing rounded corners, and which is of less area than the cushion disks 6, so that the felt will overlap the corners and substantially the same frictional function will be obtained by reason of the shape and size of disk 11, as shown in Fig. 9.

In using the invention any of the arrangement of disks shown in Figs. 5-8 may be employed. In Fig. 5 the felt disk 6 is mounted on the pebble disk 8, the projections 9 of which frictionally engage the cushion disk 6, and the disk 8 in turn is mounted on another metal disk 7, and inclosed within the cover 4 of casing 1 on the steering gear 5, as shown in Fig. 1, the cover 4 being screwed down to a moderate tension and locked with a small set-screw. The three disks 6, 8, and 7 form a smoothly operating friction clutch which will function to hold the steering post and steering gear in any particular position to which it has been directed by the steering or driving wheel 2, and will relieve the driver of the necessity of constantly maintaining a grip on the steering wheel, for the wheel will remain turned at whatever angle it has been shifted to. The disks 10 and 11 may either be substituted for the disk 8, and will function in a similar manner, as the corrugations and the rounded and squared edges of disk 11 provide a friction element relative to the felt cushion equivalent to the projections 9 of disk 8. I may position the cushion 6 between the disks 7, as in Fig. 6, either with or without the disk 8, as shown in Figs. 6 and 7, or I may omit the disk 7 and use the disks 6 and 8 as in Fig. 8. The friction disk 8 (or 10 or 11) remains stationary on the felt cushion 6 by reason of the frictional engagement therewith. The device allows a flexible control of the steering apparatus of the car, even when in mud or on rough roads, or when striking objects in the road.

What I claim is:

1. A disk cushion clutch for use in regulating the operation of steering gears, comprising a ring-shaped disk of thick material and of flexible character, and metal disks of similar shape in frictional engagement with the first-named disk, said disks being inclosed within the casing of and mounted on the steering gear the uppermost disk being

frictionally engaged by the casing of the steering gear.

2. In a disk cushion clutch for steering gears, the combination of a ring-shaped flexible disk, a ring-shaped metal disk having portions thereof frictionally engaging the first-named disk, and a second metal disk of

similar shape without the frictionally engaging portions all interposed between the steering gear casing and steering gear for frictional engagement with said members, substantially as shown and for the purposes described.

FREDERICK M. MELVIN.
